UNITED STATES PATENT OFFICE.

FRANK FUNK, OF DECATUR, ILLINOIS.

METALLIC JOINT.

SPECIFICATION forming part of Letters Patent No. 398,321, dated February 19, 1889.

Application filed July 18, 1888. Serial No. 280,298. (No model.)

To all whom it may concern:

Be it known that I, FRANK FUNK, of the city of Decatur, county of Macon, and State of Illinois, have invented certain new and useful Improvements in Metallic Joints, of which the following is a specification.

My invention is designed to join a sheet-metal body to a sheet or cast metal bottom in a manner to form a water-tight receptacle that may be subjected to a high degree of heat without affecting the joint.

In the drawings accompanying and forming a part of this specification, Figure 1 is a bottom view of a receptacle having its bottom joint partly formed in accordance with my invention. Fig. 2 is an elevation of the lower portion of a receptacle with a portion broken away to show the manner of forming the joint. Figs. 3, 4, and 5 are sectional views of a fragment of joint in various stages of completion.

The bottom *a* has the upwardly-projecting rim *a'*, to which the body *e* is secured by rivets *d*. The bottom is convex at its lower edge, and a continuation, *b*, of the body *e* extends below the rivets and forms an angle with the curved edge of the bottom. After the body has been secured to the bottom with rivets, as shown in Fig. 3, a packing, as asbestos, is tamped into the angle, as shown in Fig. 4. The joint is then completed by bending the continuation *b* over the packing and closely against the bottom, as shown in Fig. 5.

In Fig. 2 the bottom is shown as composed of cast metal. In Figs. 3, 4, and 5 both body 35 and bottom are formed of sheet metal.

The packing *c* is preferably of asbestos; but I do not consider it impossible that other substances are known or may be discovered that will meet all requirements, and therefore 40 I do not wish to be understood as confining myself entirely to that material.

In the use of my device no serious leakage is apt to occur even though the vessel is subjected to a shock that would start another 45 joint. The water or other fluid will percolate but slowly through the packing when the joining metal is somewhat displaced.

I have found the joint desirable in the construction of tank-heaters—*i. e.*, heaters submerged in tanks to prevent water from freezing—and other uses are readily apparent.

I claim—

The joint comprising the part *a*, having rim *a'*, the part *e*, riveted to the rim, the part *b*, 55 bent over on part *a*, and the packing *c*, interposed between *a* and *b*, as and for the purpose set forth.

In testimony whereof I sign my name in the presence of two subscribing witnesses.

FRANK FUNK.

Attest:

ALBERT T. SUMMERS,
L. P. GRAHAM.
